UNITED STATES PATENT OFFICE.

CHARLES S. WILLIAMSON, OF CHICAGO, ILLINOIS.

COAL-HANDLING PLANT.

1,205,303.

Specification of Letters Patent. Patented Nov. 21, 1916.

Application filed July 20, 1912. Serial No. 710,559.

To all whom it may concern:

Be it known that I, CHARLES S. WILLIAMSON, a citizen of the United States, residing in Chicago, county of Cook, and State of Illinois, (whose post-office address is care of Mead-Morrison Mfg. Co., 53 West Jackson Boulevard, Chicago, Illinois,) have invented new and useful Improvements in Coal-Handling Plants, of which the following is a specification.

It is the object of the present invention to provide means for handling coal and for loading the coal into cars, either box cars or gondola cars, the loading operation being carried out at high speed, but without smashing or disintegrating the coal even though it be in large lumps.

The characteristic features of my present invention are set forth more at length in the detailed description which is to be taken in conjunction with the accompanying drawings.

In the drawings, Figure 1, is a side elevation of part of a coal handling plant, equipped in accordance with my present invention for the ready handling and loading of lump coal. Fig. 2 is an elevation of the structure shown in Fig. 1.

The embodiment of my invention illustrated in the drawings, includes a steel bridge structure 1 mounted on suitable trucks 2 and adapted for movement along a track-way of wide gage which parallels a railroad track for the cars to be loaded. For the sake of simplicity, only the relevant portions of the complete bridge structure are shown in Fig. 1, the elevator, screens, storage bins, and the like being omitted for the sake of simplicity in the drawings.

Near the top of the bridge structure is a fifty ton hopper 3 into which "run-of-mine" coal can be dumped from the grab bucket of the traveling bridge ordinarily used with such a plant as that herein disclosed. Coal from this hopper 3 may be discharged through suitable feeders to downwardly inclined shaking screens 4 and 5, the uppermost being of large mesh, say two inch and the lowermost of smaller mesh, say one inch. These screens are shaken by means of connecting rods 6 and 7 actuated in suitable manner from a motor driven eccentric 8. Small coal passing through screens 4 and 5 is collected in suitable twenty-five ton hoppers 9 and 10 from which it may be loaded to cars in suitable manner. The larger or

lump coal is delivered from the screens across a stationary apron 11 to the platform 12 of a chain conveyer running transverse to the screens or transverse to the line of movement of the coal as it passes from those screens.

The transverse chain conveyer comprises, in addition to the platform 12, a large loading spout 13 at the forward end of that platform and receiving coal directly therefrom. The movement of coal across platform 12 and into the open upper end of spout 13 is effected by a chain conveyer extending over the sheaves 14, 15 and 16 and having flights or cross plates 17 which push the coal forward into the open end of spout 13. This chain conveyer may be driven in suitable manner as from an electric motor 18. Spout 13 is positioned to deliver coal to a side door box car and in order that the coal may not attain a dangerous or destructive speed during its descent through the spout, a plurality of retarders 19 may be placed in the spout, each consisting of a weight 20 carried on the end of a pivotally mounted arm 21 at the upper end of which is a cross board 22 in the path of the moving coal. In normal operation, coal will accumulate at the cross boards, until there is enough to lift the counter weight and so flip the retarders and release the coal.

A second spout 22 is mounted near the outer end of the transverse conveyer and is to be used for loading the coal into high side gondola cars. This spout is mounted on wheels or trucks 23 and when not in use, can be pushed back out of the way of brakemen riding on the top of box cars. When this spout 22 is in use the entrance to spout 13 is closed by a horizontal metal plate slipped in from the side of the conveyer at 24.

Loading spout 13 does not extend into the doorway of the box car to be loaded, but is supplemented by a loading structure indicated by the numeral 31.

What I claim as new, and desire to secure by Letters Patent of the United States, is:

1. In apparatus of the class described, the combination of a source of coal supply mounted on wheels and adapted to occupy two parallel adjacent rails and inclined screens over which the coal is passed, a transverse conveyer for carrying the larger lumps of coal off at right angles to said track at the bottom of the screen, and a spout communicating from said conveyer directly to the container to be loaded, said container and

all associated mechanism being mounted on a track parallel with the cars to be loaded and arranged to occupy said track alone.

2. A device of the character described, 5 comprising the combination of a supporting structure arranged along a single track comprising two parallel and adjacent rails and supported thereon upon wheels with an inclined separator, a platform extending 10 transversely of the lower end of said separator and arranged substantially below the adjacent end of the separator, an apron connecting said platform with said separator, a flight conveyer operating over said platform, and a spout extending from said platform at right angles to the supporting structure, whereby coal or the like may be sized 15 and screened and gently deposited in a car or other container without danger of breakage.

3. In a device of the character described, the combination of an inclined separator mounted on rails parallel with cars to be

filled, a conveyer extending transversely of said separator and adapted to receive material therefrom without breakage or injury, an inclined spout leading from the medial portion of said conveyer, and retarding means mounted within said spout.

4. The combination with an inclined screen 25 adapted to separate different grades of coal, a transversely extending conveyer operatively connected with the lower end of said screen for checking and conveying the large coal passing over said screen, an inclined 30 spout leading from the medial portion of said conveyer, and pivotally mounted retarding fingers extending within said spout for the purpose specified.

In witness whereof, I hereunto subscribe my name to this specification in the presence of two witnesses.

CHARLES S. WILLIAMSON.
